UNITED STATES PATENT OFFICE.

THEODORE HALL, OF BROOKLYN, NEW YORK, ASSIGNOR TO HALL & CONNOLLY, INC.,
OF NEW YORK, N. Y., A CORPORATION OF NEW YORK.

FEEDING MEANS FOR ARC LAMPS.

Application filed October 13, 1923. Serial No. 668,273.

This invention relates to feeding mechanisms for arc lamps especially projector lamps for motion or other pictures. In such lamps it is desirable to provide an automatic feed for both electrodes, both to maintain the proper arc length and the proper position of the positive crater with respect to the projector. According to my invention I provide a single means for both purposes which feeds the electrodes together at a predetermined rate in accordance with the arc length. My invention has particular reference to the contact means which governs the automatic power driven feeding means, whereby a quick break, self cleaning contact is provided.

A further object of the invention is to so design the automatic means that it does not interfere with the hand feed.

Further objects of the invention will be apparent as the description proceeds.

Referring to the drawings wherein I have shown the preferred forms of my invention,

Fig. 1 is a skeleton side elevation of the mechanism of a projector lamp in accordance with my invention.

Fig. 2 is an end view of the same, the parts being in section.

Fig. 3 is an elementary wiring diagram.

Fig. 4 is a view corresponding to Fig. 1, of a modified form of the invention.

Fig. 5 is a detail of one of the contacts of Fig. 4.

The skeleton of a projector is shown in Fig. 1, 1 representing the reflector, 2, the negative carbon, 3, the positive carbon, and 16 the back plate. Each holder 4 and 5 is threaded on a feed screw 6, the threads having an opposite pitch at the two ends as at 7 and 8 so that rotation of the screw will feed both electrodes together (or apart). Also the pitch of the two threads is designed so that each electrode is fed at its proportionate rate of consumption to maintain the positive crater at the focus of the projector. The positive electrode is shown as yieldingly clamped in its holder by spring pressed plunger 9.

For effecting the automatic feed, I pro-

vide a motor 10, which in this instance turns feed rod 6 by means of a pawl and ratchet mechanism. The motor is shown as provided with a worm 11 meshing with worm wheel 12. On the shaft 13 of said wheel is crank pin 14 to which is connected connecting rod 15. Said rod in turn is pinned to pawl carriage 17, carrying pawl 18. The cooperating ratchet wheel 19 may be directly mounted on feed rod 6 on which may also be located the hand feeding knob 20.

I prefer to reciprocate the carriage only when feeding is desired and therefore provide means for governing the motive means as feeding is necessary. For this purpose a control or voltage regulator coil 22, connected preferably across the arc, is provided. Said coil is shown as in the form of an electro-magnet having a core 23 and armature 24 pivoted at 25. Said armature is provided with a downwardly extending arm 26 having a contact 27 at its lower end. An adjustable spring 28 normally holds the arm 26 to the left in Fig. 1 against stop 29, thus holding armature 24 up. As the arc length increases, the strength of the coil increases until the tension of spring 28 is overcome and contact 27 brought against cooperating contact 30, which is located on reciprocating carriage 17. Thus, whenever the contacts are closed, a relative movement is imparted to the contacts to keep their surfaces clean and bright.

Preferably, I construct contact 30 with an inclined surface 31 which slopes outwardly toward contact 27 in the direction of pawl 18. By this means I provide for a quick, definite break of the contact and insure its always occurring when the pawl is up, i. e., out of engagement with the ratchet, thus leaving the screw 6 free to be fed by hand. That this is so will be appreciated when it is remembered that the pull of magnet 22 on armature 24 varies inversely as the square of the air gap, and directly in accordance with the current strength due to the voltage drop across the arc. Thus when the arc is too long and coil 22 is strong enough, contacts 27 and 30 are closed and

remain closed under the pull of the magnet on the armature is overbalanced by spring 28. The air gap is of course longest at the high point of contact 30 and therefore, the 5 pull is weakest at that point. Hence the magnetic pull will first be overcome at this point. To assist this action the tension of spring 28 is so designed that its rate of increase for a given elongation is not nearly 10 as great as the increase in magnetic pull on the armature for a corresponding shortening of the air gap. This construction, it should be noted also has the decided advantage that the two contacts are held together much 15 more tightly during the greater portion of their movement than is ordinarily the case, since the pull of magnet 22 on contact 27 is greater at all positions of contact 30 than at the high spot, where the contact is made. 20 One modification that my invention may assume is shown in Fig. 4. According to this modification, instead of the reciprocating carriage, a shaft 40 is rotated from motor 10', as by gears 41 and 42. Said shaft 25 rotates feed screw 6' by means of a worm 43 and worm wheel 44. To permit ready hand feeding, the worm wheel may be detachably connected to shaft 6' as by friction clutch 45, which is mounted on a sleeve on 30 the end of sub shaft 50 and resiliently pressed against a face of the worm wheel by spring 46 and pinned to shaft 6' by pin and slot connection 47, 48. To feed by hand, the operator first pushes in on the 35 hand wheel 20' to disengage the clutch and then rotates the hand wheel in the desired direction.

As before, I mount one of the contacts 27', 30' on the member 40 actuated by the motor 40 to cause relative transverse movements of the contacts. In this instant contact 30' is made circular and is, as before, provided with a high spot 50 (see also Fig. 5). Current is shown as led into contact 30' by 45 brush 51 connected to motor 10'. Other parts in this figure are numbered to correspond to the parts of Fig. 1, and their operation will be understood without repetition.

50 From the foregoing the operation of my invention will be clear. As long as the arc is of the proper length, magnet 22 is unable to overcome the pull of spring 28, and all feed parts are stationary. When the 55 arc length becomes too great, contacts 27 and 30 are closed, starting motor 10, causing rubbing on the contact surfaces, and starting the automatic feed which continues until spring 28 overcomes the decreasing 60 magnetic pull. This break of the contact will always be sharp and occur at the high point on contact 30, thus leaving the hand feed free. It will of course be understood that there need not be a complete break between the contacts 27 and 30 to effect the

purpose of my invention, since if graphite or similar contacting surface is employed for at least one of the contacts, a stoppage of the motor may be secured by decreasing the pressure between the contacts to a small 70 amount, so that the resistance across the gap will be sufficient to prevent enough current flowing to operate the motor.

In accordance with the provisions of the patent statutes, I have herein described the 75 principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and 80 others omitted without interfering with the more general results outlined, and the invention extends to such use. 85

Having herein described my invention what I claim and desire to secure by Letters Patent is:

1. In a feeding mechanism for projector lamps, the combination with a control coil connected across the arc, of motive means for effecting the feed, a pair of contacts governed by the coil and in circuit with said means to render the same operative, one of said contacts having an inclined face and being connected to said means so as to be moved transversely to the other contact for 100 the purpose specified.

2. In a feeding mechanism for projector lamps, the combination with a control coil connected across the arc, of motive means for effecting the feed, a pair of contacts 105 governed by the coil and in circuit with said means to render the same operative, one of said contacts being movable toward and away from the other, and the last-named contact having an inclined face and being connected to said means so as to be moved transversely to the other contact, the contact face of the first-named contact being polished and the contact moved by the movement of the last-named contact. 115

3. In a feeding mechanism for projector lamps, the combination with a control coil connected across the arc, of motive means for effecting the feed, a carriage reciprocated thereby, pawl and ratchet mechanism for feeding both electrodes by the reciprocation of the carriage, a pair of contacts the relative position of which is governed by said coil, one of the contacts being mounted on said carriage to be reciprocated thereby 120 and having an inclined contacting surface. 125

4. A feeding mechanism as claimed in claim 3 wherein the surface of the reciprocatory contact slopes toward the other contact in the direction of the pawl, whereby

the contact breaks when the pawl is out of engagement with its ratchet for the purpose specified.

5. In a feeding mechanism for arc lamps, the combination with a control coil, of an armature governed thereby, a pair of contacts one of which is controlled by said armature, and means for moving said con-

tacts relative to one another to vary the air-gap of said armature and thereby the pressure between said contacts for the purpose specified.

In testimony whereof I have affixed my signature.

THEODORE HALL.
